WELTING AND SHOEMAKING THEREWITH

William C. Vizard, Brockton, Mass., assignor, by
mesne assignments, to Barbour Welting Com-
pany, Brockton, Mass., a copartnership com-
posed of Perley E. Barbour, Walter G. Barbour,
and Richard H. Barbour

Application April 6, 1933, Serial No. 664,722

18 Claims. (Cl. 12—142)

This invention relates to the manufacture of
welting for incorporation in shoes having a short
upper, i. e. an upper so cut that there is no excess
margin or lasting allowance to lie under the in-
5 sole.

A short upper effects a great saving of upper
stock and by using the welt of this invention
sufficient stock is gained to enable the vamp cutter
to cut five vamps where only four could be ob-
10 tained before. A further saving is gained if the
shoe is welted about the heel as well as about the
forepart. The welt is so prepared and fitted that
it eliminates the necessity for excess margin on
the upper, formerly used as a lasting allowance.
15 The welt reinforces the lower edge of the short
upper, provides a stub-proof toe on shoes for the
youngsters, and forms a waterproof seam that is
highly advantageous, particularly in the service-
able type of sport shoe. Furthermore there is a
20 saving of many shoemaking operations in the
manufacture of shoes with this welting over those
required for Goodyear shoes, for example insole
channeling and its allied operations, vamp trim-
ming, inseam trimming and bottom filling. It
25 also substitutes the comparatively cheap Singer
or Puritan dry thread sewing machine for the
more expensive Goodyear welt and turn sewing
machine in the step of securing the welt to the
upper, and other and possibly cheaper securing
30 means may be used such as metallic fasteners.
The shoe having this welt incorporated has a
floating insole unchanneled like a McKay insole
but without the McKay stitching. This provides
increased flexibility and since the insole and out-
35 sole contact each other no discomforting insole
gutter can be formed by length of wear.

The novel welting comprises a pair of edge
flaps within which the short upper is secured, the
two flaps reinforcing the upper both inside and
40 outside and preferably being integral with the
outturned welt extension to insure a weather-
proof shoe. The upper may be preliminarily se-
cured to the inner flap alone or to both flaps
and in the former event the outer flap may be
45 secured to the upper either by cement or a
through-and-through fastening as may be de-
sired.

The main objects of this invention are to pro-
50 duce a welt adapted for securement to the lower
edge of an upper too short to overlast in such
manner that on lasting the shoe the welt exten-
sion will provide an outturned flange in position
for bottoming with an outsole, and to produce a
55 shoe having the advantages hereinbefore referred

to and such others as may appear from the fol-
lowing description.

To the accomplishment of these objects and
such others as may hereinafter appear, as will
readily be understood by those skilled in the art, 5
the invention comprises the welting and the shoe
and the process of manufacture thereof as here-
inafter described and then particularly pointed
out in the appended claims.

The invention will best be understood by refer- 10
ence to the accompanying drawings, in which:

Figure 1 shows a portion of a strand of grain
leather used as a blank;

Fig. 2 shows the welting strand of Fig. 1 split
at one edge to produce two upper embracing flaps 15
and scored to facilitate turning these flaps up-
ward relatively to the welt extension;

Fig. 3 shows how the welting strand of Fig. 2 is
manipulated while securing a welt to a short
upper; 20

Fig. 4 shows an alternative method of securing
the novel welting of this invention to a short
upper;

Fig. 5 shows a lasted shoe, in section, using a
welted short upper according to this invention; 25

Fig. 6 is a view of a completed shoe, in per-
spective, the vamp being broken away to show the
bottoming, outsole stitching and weatherproof
seam provided by the novel welt;

Fig. 7 shows a fragment of a shoe, in section, 30
illustrating the alternative welt and upper secure-
ment of Fig. 4, and also illustrating a skived outer
welt flap applicable to dress shoes;

Fig. 8 shows a fragment of a shoe, in section,
illustrating a skived inner welt flap for heavy 35
duty shoes to provide a smooth inner surface;

Fig. 9 shows a portion of the novel welting
modified by the addition of strip material con-
stituting lasting allowance; and

Fig. 10 shows a fragment of a shoe, in section, 40
illustrating the function of the added lasting al-
lowance.

In the following description the manufacture
and use of the welting of this invention will, for
simplicity, be confined to the processing of grain 45
leather, but it should be distinctly understood
that the usefulness of this invention is not lim-
ited to leather because any suitable welting ma-
terial may be processed and used in like man-
ner; nor are dimensions given because they vary 50
greatly with the size and kind of shoe for which
the welting is made. The general field of useful-
ness of the welting includes children's, growing
girls', misses', little gents' and boys' shoes; work 55

shoes for all ages; and sport shoes, particularly of the serviceable type.

In the embodiment of the invention illustrated by Figs. 2, 3, 5 and 6 a grain leather strand 10 is edge split transversely and longitudinally producing a grain faced flap 12 and a flesh flap 14 integral with a grain extension 16. The location of the edge slit may vary according to the weight desired in either flaps but ordinarily centrally of the edge is satisfactory for a majority of welt sizes. The strand 10, before, after or during edge splitting, may be scored as at 17 along the line of joinder of the flaps and extension to facilitate forming-up the welt; similarly one or more parallel, longitudinal indentations or grooves may be lightly impressed in the grain face of the flaps 12 to serve as a guide for the stitching room operator when securing the welt to the shoe upper.

Having prepared a short upper, i. e. one that lacks the extra length necessary to provide lasting allowance, and having prepared the welt, these two parts of the shoe are secured together. In one method (Fig. 3) the lower margin of the upper is inserted between the flaps 12 and 14 and secured by one or more rows of through-and-through stitching laid in the guiding grooves 18. The welt, in its final form, has a right-angular cross-section the two flaps standing substantially perpendicular to the plane of the welt extension. In turning the two flaps upward along the fold line 17 the grain faced flap slides upward on the flesh flap. If the upper is stitched while the welt is flat the grain faced flap might buckle on final forming-up, whereas this exposed flap should be flat and lie smoothly against the outer face of the upper. Accordingly the two flaps may be bent upward as shown in Fig. 3, prior to stitching with the Singer, Puritan or other suitable dry thread sewing machine; one or more rows of stitching 20 being used as may be desired. It will be observed that the upper 22 is received between the two flaps and all three layers are secured together. Shoes in which this novel welt is incorporated preferably have a lining 24 of the usual length for lasting in under the insole and this merely hangs down loosely (see Fig. 3) in front of the bed of the sewing machine during the stitching of the welt to the upper.

The welted upper is then assembled on a last with an insole 26. At this stage or preliminarily thereto the extension 16 is outturned and the embraced edge of the upper lies below the bottom of the last. The lining 24, if present is lasted in and may be fastened by cement, or otherwise, to the insole (Fig. 5). Any approved method of lasting the welted upper, to bring the flesh face of the welt extension into substantially the plane of the bottom face of the insole, may be employed.

Bed lasting has been found to be efficient for this purpose. If required after lasting, the welt is pounded down to furnish what is known as a level bottom for receiving an outsole without any filler. Any insole tacks are removed to leave a floating insole in the finished shoe and the shoe is then bottomed with an outsole 28 (Fig. 6), the contacting faces being preferably first cemented and edge pounded for a tight joint along the welt. The outsole is fastened, as by an outseam 30, preferably stitched close to the shoulder to maintain the welt tight against the edge of the insole. Later shoe-making steps may be as usual.

Fig. 6 represents the bottoming of a work shoe as just described in which the welt flap 12 covers

the upper to a width of five to six sixteenths of an inch and is of rugged construction to give protection against hard wear. As illustrated the entire upper is welted the welt being skived and lapped as shown at 32. Some manufacturers may apply the welt only to the vamp in which case the ends of the welt are butted and tucked in at the shank as in Goodyear work.

For dress shoes the welt may be secured to the upper as shown by Fig. 4. The flap 12 is lifted from the flap 14 and the upper 22 is stitched solely to the flesh flap. The grain faced flap 12 is then cemented to the upper which may be chamfered or roughened on its grain face to aid permanent adhesion. A further refinement may consist in skiving the flesh face of the outer flap 12 to a feather or near feather edge to avoid undue thickness or awkward lines in the finished shoe. This is shown at 34 in Fig. 7. Again, with the heavier weight of weltng it may be desirable to skive the flesh flap for a smooth contour beneath the lining as shown at 36 in Fig. 8. Any combination of skiving either the welt flaps or the upper may be employed to obtain comfort or tightness. The upper after being welted in any of these ways is processed in any suitable manner.

The modification of Figs. 9 and 10 aids in lasting. Here the weltng, formed as hereinbefore described, is provided with an attached piece of sheet material which serves as lasting allowance. The weltng may have a strip of canvas, upper leather or the like attached to lie at the outer face of the flesh flap 40, which constitutes the outer of the two upturned flaps, by cement or stitching and having a width substantially that of the weltng. The proportions of the grain faced flap 42 and of the extension 44 are not altered. The extra piece may be attached to the weltng either before or while the upper is being attached and if the latter then the dry thread seams 46 serve to hold all of the parts together. The securement 47 of the strip provides a lasting allowance or free flange 48 that is extendable inward of the welt extension as shown in Fig. 9. This free flange is seized by the laster in drawing the welted upper over the last and is secured to the insole as hereinbefore described for the lining 50. Littleway process staples are illustrated in Fig. 10.

Shoes manufactured as herein described have the general appearance of shoes sewed with a reverse welt but the present invention greatly improves that style of shoemaking by reason of the additional welt flap inside the upper which is not only a reinforcement for the upper but binds the welt in position and serves as an anchor for the welt extension. Those skilled in shoemaking will recognize the efficient waterproof seam between the welt and upper and the weatherproof feature provided by the upward continuation of the welt extension without a break in the material. Water, sand and dirt have no opportunity for entry into the shoe. The floating insole and contacting outsole without filler, provide great flexibility even in the larger work shoes having a heavy duty outsole. The saving of upper stock, as stated, is considerable and the process may be practised with all kinds of upper stock and for all sizes of shoes, merely selecting a welt strand of proportionate size. While the appearance of a thread seam or seams along the exposed flap of the welt will probably be preferred by shoe manufacturers, it being understood that such seams may be used on dress

shoes as well as work shoes, it is within the scope of the invention for those who desire decorative effects to use any kind of ornamental fastening available. The upstanding grain faced welt flap 5 also lends itself to many forms of ornamentation in combination with stitched seams. Preferably the exposed flesh edge of the grain faced flap is colored to conform to the color of the upper (see Fig. 6).

10 Those skilled in the manufacture of shoes will recognize that the process hereinbefore described may be varied to suit particular conditions. For example, it is within the scope of the invention to insert the short upper between the upper embracing flaps of the welt while the welt is in a flat or unformed condition and then attach the welt to the upper by stitching or otherwise, any slight buckling of the outer flap 12 being ironed out after lasting. Such a mode of securing is 15 desirable for the larger and less flexible welts for work shoes and the like. Bending heavy welts on the last to angular form is facilitated by the fold scoring; in fact the welt will preferably be formed-up before being soled so that after flattening out reforming on the last is easily accomplished especially as the flesh flap will stretch somewhat during the welt beating operation. Additional protection against the weather or other harsh conditions may be gained by cementing one or both of the upper embracing welt flaps with a waterproof cement such as 20 compo before the upper is stitched. On shoes fitted with a continuous welt the joint may be made by skiving or by butting the welt ends as the manufacturer may desire, the welt ends being so cut that the joint or splice is both neat and tight.

25 In the following claims the term "upper" is used to include either only the forepart of the upper when the welt is not to be applied about the heel end of the shoe, or a complete upper when the shoe is to be completely welted.

30 Reference is made to the co-pending application of Pearl C. Arnold Ser. No. 664,742, filed of even date herewith, claiming an improvement on the invention herein disclosed, except that the modification of Figs. 9 and 10 herein is acknowledged to be subordinate to the invention claimed in said co-pending Arnold application.

35 The nature and scope of the invention having been indicated and its preferred embodiments and the method of its manufacture having been specifically described, what is claimed as new, is:—

1. In a welted shoe of the type having an upper 55 too short to overlast, a welt comprising a strand of weltng material having one edge split transversely forming two flaps at said edge integral with the welt extension, said flaps being both turned substantially perpendicular to the welt extension for embracing said short shoe upper.
2. The invention according to claim 1 in which at least one of said welt flaps is tapered outwardly to a thin edge.
3. In a welted shoe of the type having an upper 65 too short to overlast, a grain leather weltng strand consisting of a grain extension and grain faced and flesh edge-flaps both of substantially the same weight and integral with said extension, said two flaps being bent together into parallel and upstanding position relative to the grain face of said extension to lie with said grain faced flap outside and said flesh flap inside the lower edge of the short upper.
4. Weltng for shoes having a short upper comprising strip material bent to right-angular form 75

along a longitudinal fold line, one flange of said angular weltng constituting the welt extension and its other flange consisting of inner and outer flaps adapted to embrace said short shoe upper between them. 5

5. Weltng according to claim 4 in which said welt extension consists of solid material and said two flaps extend from and are integral with one edge thereof.

6. Weltng according to claim 4 having an additional piece of strip material constituting lasting allowance attached to the outer of the two flaps.

7. In a welted shoe of the type having an upper too short to overlast, grain leather weltng comprising a solid grain extension at one margin and contiguous grain faced and flesh flaps at the other margin, said flaps and said extension being folded with the grain flap inside along their longitudinal line of joinder to produce weltng having a substantially right-angular cross section with the extension forming an outturned flange about the upper, and an outsole secured to said flange. 15 20

8. The invention according to claim 7 in which an additional piece of strip material is attached to lie at the outer face of said flesh flap and is extendable from said extension to provide lasting allowance. 25

9. Weltng for shoes having a short upper comprising a welt extension having two separable flaps at one edge thereof adapted to be turned upward relatively to said extension to receive said short upper between them, and an additional piece of strip material attached to the flap which is outside when in upturned position and having a free flange constituting lasting allowance. 30 35

10. A shoe comprising an insole, an upper too short to overlast, a welt having its extension turned outward from the insole and having a pair of upstanding flaps adapted to receive said upper between them, said upper being secured within said flaps, and a suitably secured outsole bottoming the shoe. 40

11. A shoe according to claim 10 in which said welt consists of grain leather and said flap at the outer face of the upper is grain faced. 45

12. A shoe comprising an insole, an upper too short to overlast, a welt having its extension turned outward from the insole and having a pair of upstanding flaps adapted to receive said upper between them, said upper being secured within said flaps, a lining of lasting length secured to the under face of the insole but unsecured to said welt, and a suitably secured outsole bottoming the shoe. 50 55

13. The method of making shoes which includes cutting an upper too short to overlast, supplying a welt having two separable flaps at one edge of its extension, attaching the lower edge of said upper between and to said flaps, assembling an insole and said welted upper on a last, lasting, and applying an outsole to said insole and to the welt extension outturned to lie substantially in the plane of the insole. 60 65

14. The method described by claim 13 in which the upper has a lining of lasting length attached thereto and said lasting is effected by drawing said lining upward and inward over the insole and said welted edge of the upper against the edge of the insole. 70

15. The method described by claim 13 in which said upper is attached by stitching to the welt flap at its inner face and by cementing to the welt flap at its outer face. 75

16. The method of making shoes which includes cutting an upper too short to overlast, supplying a welt strand substantially wider than is required for a welt extension having one edge 5 split longitudinally to provide two flaps, bending said two flaps at substantial right angles to said extension and then securing the lower edge of the upper between said flaps providing an outturned flange thereon, assembling an insole 10 and said welted upper on a last, lasting by stretching the upper until the outturned flange is drawn opposite the edge of the insole—or it may be drawn substantially level with the bottom of the insole—and applying an outsole to 15 said insole and to the outturned flange provided by said welt extension.
17. A welted shoe comprising an upper too short to overlast, a welt formed of strip material bent to a right-angular form along a longitudinal fold line, one flange of said angular welt 20

constituting the welt extension and its other flange consisting of two flaps within which the lower edge of the short upper is secured, said extension forming an outturned flange at said lower edge of the upper, and an outsole secured 5 to said out-turned flange.

18. The method of making shoes which includes cutting an upper too short to overlast, supplying a welt having two separable flaps at one edge of its extension, attaching the lower 10 edge of said upper between and to said flaps, assembling said welted upper on a last and turning the welt extension outward forming an out-turned flange at said lower edge of the upper, 15 lasting to conform said upper to the last and said welt to the shape of the last bottom, and bottoming the shoe by securing an outsole to said out-turned flange.

WILLIAM C. VIZARD. 20

CERTIFICATE OF CORRECTION.

Patent No. 2,039,370.

May 5, 1936.

WILLIAM C. VIZARD.

It is hereby certified that error appears in the printed specification of the above numbered patent requiring correction as follows: Page 2, first column, lines 9 and 17, for the word "flaps" read flap; page 3, first column, line 24, for "soled" read sold; and that the said Letters Patent should be read with these corrections therein that the same may conform to the record of the case in the Patent Office.

Signed and sealed this 9th day June, A. D. 1936.
